UNITED STATES PATENT OFFICE.

NATHAN CHESLER, OF BROOKLYN, NEW YORK.

SWITCH PLATE.

Application filed December 8, 1927. Serial No. 238,594.

This invention relates to a switch plate or receptacle for a switch adapted to receive a plug.

More particularly this invention relates to 5 a duplex receptacle switch adapted to receive two switch plugs.

The general object of my invention is to provide a glass switch plate adapted for a duplex receptacle switch and having a structure which is adapted to receive a fastening screw for holding the plate in position and without engaging the fastening screw with the material of the glass plate.

The invention furthermore has for its object to provide a glass switch plate having a duplex bushing adapted to be coordinated with a duplex receptacle switch and having a cross member at a medial portion of the bushing formed with a screw hole to take the fastening screw which engages directly with the duplex receptacle switch, thereby carrying out the first stated object of avoiding engagement of the fastening screw directly with the material of the glass switch plate.

Reference is to be had to the accompanying drawing forming part of this specification, it being understood that the drawings are merely illustrative of one example of the invention.

Figure 1 is a face view of a glass plate for a duplex receptacle switch;

Figure 2 is a sample longitudinal section taken through the glass plate and its bushing showing the same in association with a duplex receptacle switch of known form shown partly broken out;

Figure 3 is a face view of the glass switch plate alone with its bushing and without the switch;

Figure 4 is a rear view of the bushing without the packing element; and

Figure 5 is a detail in cross section taken transversely through the bushing and its packing element showing the bushing before 45 certain members are bent over the packing element.

In the illustrated example of my invention the numeral 10 designates a known form of duplex receptacle for plugs, and the numeral 11 indicates the receptacle units of said switch. As the switch is of known form no further description needs to be given.

The numeral 12 indicates a glass switch plate forming part of my present invention, 55 and the numeral 13 the bushing in the opening provided in said glass plate, while the nu-

meral 14 indicates a packing element held in position by members 19 the bushing being bent thereover.

As seen best in Figure 3, glass switch plate 60 12 is formed with an opening having an end portion 15 for almost a complete circle, said end portions being connected by a large slot or complementary open portion 16. The opening receives the switch units 11.

The bushing designated generally by the 65 numeral 13 has a transverse bridge piece 18 between two circular openings 17 registering with the end open portions 15 in the glass plate 12. At opposite sides of the bushing 13 there are formed bent members 19 rearwardly 70 directed from the face of the bushing and which are bent over the packing element 14.

In Figure 4 at the right and in Figure 5 I 75 have shown the members 19. I have shown said members before being bent over the packing element 14 and have designated said unbent members in Figure 4 and Figure 5 by the numeral 119.

On the bridge piece 18 and at diametrically opposite sides of the openings 17 of the bushing 13 I form lips or flanges 20 which are adapted to constitute stops limiting the movement of the bushing and the switch plate 12 on to the switch or duplex receptacle 10, the intervening or packing element 14 forming the member contacting with switch or receptacle 10 when the switch and plate with its bushing are assembled.

The bridge or cross bar 18 of the bushing is 80 formed with a hole 21 (Figure 4) for receiving a fastening screw 22. The usual duplex switch or receptacle 10 has a screw hole on the transverse medial line thereof, and the screw 22 passes through the hole 21 of bridge 85 10 and into the usual screw hole of switch 10.

The cutaway portion 16 of the switch plate 12 accommodates the formation of the bridge 18 while the latter and bushing 13 100 generally conform to the openings 15, 16 in the switch plate in Figure 3. The bushing adds to the esthetic appearance of the switch or receptacle 10 and esthetic features are further promoted by the character of the glass 105 switch plate 12 which in practice is mirrored.

It is to be noted that screw 22 which serves to firmly unite the bushing and plate to the switch 10 does not engage the glass switch 110 plate 12, the connection being between the cross bar of the bushing 12 and the switch 10.

Breakage is thus avoided and ample material is available for the engagement of the screw 22.

I would state furthermore that while the 5 illustrated example constitutes a practical embodiment of my invention I do not limit myself strictly to the exact details herein illustrated, since manifestly the same can be considerably varied without departure from 10 the spirit of the invention as defined in the appended claims.

I claim:

1. A switch plate formed of glass and having an opening the end portions of which are 15 rounded, the defining edges approaching complete circles, said plate having a space between and complementary to said rounded end portions, and a bushing having end portions conforming approximately to said end 20 portions of the opening in the glass plate, and having a bridge, members of which are accommodated in said complementary space of said switch plate.
2. A switch plate formed of glass and having an opening the end portions of which are 25 rounded, the defining edges approaching complete circles, said plate having a space between and complementary to said rounded end portions, and a bushing having end portions conforming approximately to said end 30 portions of the opening in the glass plate, and having a bridge, members of which are accommodated in said complementary space of said switch plate, together with flanges on 35 said bushing at diametrically opposite sides, and lips on said bridge and on the bushing at the portions diametrically opposite said bridge.
3. A glass switch plate having an opening, 40 the end portions of which have a round defining edge approaching a complete circle, and a central opening connecting and complementary to the round portions, and a bush-

ing in said opening, the end portions of the bushing presenting round openings, and an 45 intermediate portion of the bushing having a transverse bridge, said openings in said switch plate and in said bushing adapted to accommodate the units of a duplex receptacle switch.

4. The herein described switch plate assemblage, comprising a glass plate having an opening presenting round end portions and an intermediate connecting open portion, and a bushing conforming generally to the end 50 portions of the opening in said switch plate and having a bridge formed with members accommodated in the said connecting open portion of the bridge, side flanges on each of the end portions on the bushing and directed rearwardly, and lips on said bridge of the bushing and on portions of the bushing diametrically opposite said bridge, said lips being parallel with the general plane of the switch plate.

5. The herein described switch plate assemblage comprising a glass plate having an opening presenting round end portions and an intermediate connecting open portion, and a bushing conforming generally to the end 55 portions of the opening in said switch plate, and having a bridge formed with members accommodated in the said connecting open portions of said plate, side flanges on each of the end portions on the bushing and directed 60 rearwardly, and lips on said bridge members and on portions of the bushing diametrically opposite said bridge, said lips being parallel with the general plane of the switch plate, together with a packing element, the said side flanges of the bushing being bent over said 65 packing element.

Signed at New York in the county of New York and State of New York, this 6th day of December, A. D. 1927.

NATHAN CHESLER.
